CARD TABLE ASH RECEPTACLE

Filed July 25, 1930

Andrew L. Duhr.

INVENTOR

BY *Victor J. Evans*

ATTORNEY

WITNESS: *George L. Ogle*

UNITED STATES PATENT OFFICE

ANDREW LEROY DUHL, OF DENNISON, OHIO

CARD TABLE ASH RECEPTACLE

Application filed July 25, 1930. Serial No. 470,718.

This invention relates to improvements in ash receptacles and has for an object the provision of a receptacle which may be quickly attached to or removed from a table for the convenience of smokers.

Another object of the invention is the provision of a receptacle which is especially designed for attachment to a card table in a manner to be positioned out of the way of the players, yet within convenient reach.

For the above purpose, the invention provides a receptacle which may be removably seated within a crotch formed at the juncture of a table leg and its brace, as found in the usual folding card table, means being provided for engagement with the leg and brace, so that the receptacle may be readily positioned or removed.

With the above and other objects in view, the invention further includes the following novel features and details of construction, to be hereinafter more fully described, illustrated in the accompanying drawing and pointed out in the appended claims.

In the drawing:—

Figure 1 is an elevation of a portion of a folding card table with the invention applied.

Figure 2 is an elevation of the invention per se.

Figure 3 is a top plan view of the same.

Figure 4 is a section on the line 4—4 of Figure 3.

Figure 5 is an elevation at right angles to Figure 2.

Figure 6 is a section on the line 6—6 of Figure 4.

Referring to the drawing in detail wherein like characters of reference denote corresponding parts, the reference character 10 indicates a receptacle which is preferably made of metal and which is provided with downwardly and inwardly tapered walls which form a point at the bottom of the receptacle.

The receptacle is provided at one side with a notch 11 which is designed to receive the leg 12 of a folding card table 13. This notch is rectangular in cross section and is so proportioned as to readily receive and engage three of the sides of the leg 12.

Extending from the upper edge of the receptacle 10 at a point diametrically opposite the notch 11, are spaced lugs 14 and these lugs are adapted to engage upon opposite sides of an inclined brace 15 which connects the table and the leg 12 in a manner to hold the leg extended, or to permit of the leg being folded inwardly beneath the top of the table.

Extending from the inner wall of the recess 11 is a horizontally disposed supporting arm 16 which is cross sectionally curved and which will act as a tray for conveniently holding a cigar or cigarette.

Extending also from the upper edge of the receptacle 10 are finger pieces 17 which provide convenient means for handling the receptacle.

When the receptacle is positioned as shown in Figure 1 of the drawing, the recess 11 will engage the leg 12 as previously described, while the lugs 14 will engage upon opposite sides of the brace 15 with the bottom or pointed end of the receptacle seated within the crotch formed at the juncture of the leg and brace, as clearly shown in Figures 1 and 4 of the drawing. The receptacle may be readily removed by grasping either of the finger pieces 17 and lifting the receptacle directly upward, and may be replaced by merely setting the receptacle within the crotch.

The receptacle is adapted for use at any corner of the table, and for this reason, two of the finger pieces are provided so that one finger piece will extend outward to be conveniently grasped by the user.

The invention is susceptible of various changes in its form, proportions and minor details of construction and the right is here reserved to make such changes as properly fall within the scope of the appended claims.

Having described the invention what is claimed is:—

1. In combination, a table having an inclined brace connecting the legs and top, a receptacle having a vertically disposed recess in one side to receive one of the legs of the table, spaced lugs extending from the

other side of the receptacle to detachably engage the leg brace, and a horizontally disposed supporting arm at the upper edge of the recess.

5. In combination, a table having an inclined brace connecting the legs and top, a receptacle having a vertically disposed recess in one side to receive one of the legs of the table, spaced lugs extending from the other side of the receptacle to detachably engage the leg brace, and finger pieces extending from the upper edge of the receptacle.

10. 3. In combination, a table having inclined braces connecting the legs and top, a receptacle provided with a notch for removably engaging the receptacle with the table leg, and means formed integral with the receptacle at a point diametrically opposite the notch for removably engaging the receptacle with the braces.

15. 4. In combination, a table having a vertically disposed recess in one side to receive one of the legs of the table and spaced lugs extending from the other side of the receptacle and diametrically opposite the recess to detachably engage the brace members.

20. 5. In combination, a table having an inclined brace connecting the leg and top, a receptacle having a vertically disposed recess in one side to receive one of the legs of the table, spaced lugs extending from the other side of the receptacle to detachably engage and straddle the brace members, and finger pieces extending from the upper edge 25 of the receptacle at points between the spaced lugs and the vertical recess.

In testimony whereof I affix my signature.

ANDREW LEROY DUHL.
